SHOE CONSTRUCTION

Edna S. Payne, New York, N. Y.

Application April 28, 1941, Serial No. 390,658

3 Claims. (Cl. 36—2.5)

This invention relates to shoe construction and more particularly to a combination shoe and sock adapted to beach wear or the like.

Beach shoes are usually of such a nature as to be unsuitable for swimming or, when so constructed as to be suitable for swimming, usually afford insufficient protection to and support of the foot. A beach shoe, particularly for ladies' wear, should not only be attractive in appearance and structurally amenable to suitable decoration, but should also provide support and protection to the foot comparable to that afforded by a street shoe.

Most women are accustomed to wearing high heeled shoes, extended wear of which causes a degree of contraction of the Achilles' tendon sufficient at least to result in discomfort when the foot is not supported by a high heel. Furthermore, extended wear of such shoes results in some structural change of the arch of the foot, which becomes accustomed to the type of support afforded by the high heeled shoe, and which accordingly tires when not so supported. Most beach shoes which provide the foot support to which women's feet are accustomed are accordingly but little different from street shoes, except in the material of which they are made, and the decoration. Such shoes are clearly ill suited to swimming and strolling on a beach, and have the further disadvantages of substantial expense and inability to wear well under the conditions to which they are subjected in normal use.

Accordingly it is among the objects of my invention to provide a shoe for beach wear or the like which is inexpensive, yet attractive in appearance, durable under conditions of its use, and which provides proper support to and protection of the foot.

The invention accordingly consists in the features of construction, combinations of elements, and arrangements of parts as will be exemplified in the structure to be hereinafter described, and the scope of the application of which will be indicated in the following claims.

In the drawing, which illustrates one form of my invention,

Figure 1 is a perspective view of my shoe;

Figure 2 is a perspective view of the sock which forms a part of my shoe; and

Figure 3 is an enlarged sectional elevation of my shoe.

Similar reference characters refer to similar parts throughout the various views of the drawing.

In Figure 1, I have shown a woman's foot

wearing my shoe, the shoe, in general, comprising an outer shoe generally indicated at 10 and an inner shoe or sock generally indicated at 25. Shoe 10 includes a heel 11 which preferably approximates in height the heel of a conventional high heeled street shoe. As is more clearly shown in Figure 3, heel 11 has secured thereto a sole 12 having a rear portion 12a conforming to the shape of the back of the heel, and a forward portion 12b which extends from heel 11 under the arch 13 of the foot. Sole 12, and particularly portion 12b thereof, is preferably sufficiently rigid to form an arch support for the foot, and if desired the sole may be lined with an inner sole 14 formed from some material such as sponge rubber. Inner sole 14, accordingly, provides a cushioned support for the heel and arch, and also acts in an anti-friction capacity in preventing the foot from sliding forwardly out of the heel of the shoe.

Referring back to Figure 1, shoe 10 is provided with sides 15 and 16 which are secured to heel 11 in any suitable manner, and which preferably are fabricated from a water-proof or water-resistant material. Sides 15 and 16 of the shoe may be held together in any suitable manner as by an elastic strip 17. Another elastic strip 18 may also be attached to sides 15 and 16 to prevent shoe 10 from dropping off the foot as the wearer walks along.

The manner of connecting sides 15 and 16 to heel 11 may be one which is conventional in shoes of this type, and the material from which heel 11 is formed may be any suitable material, such as cork, rubber, a plastic, or other material which is sufficiently rigid to provide support, but which is light in weight so as not to act as an anchor to the wearer's foot. It accordingly will now appear that shoe 10 structurally provides substantially all of the support to which a woman's foot is accustomed, in that its heel 11 is of sufficient height not to strain the Achilles' tendon, and sole 13 is of sufficient rigidity and length as to provide ample support to the arch. It might be noted that inner sole 14 preferably extends a short distance beyond sole 12 so as to protect the arch of the foot against the end of sole portion 12b, accordingly preventing this portion of the sole from cutting into or chafing the foot.

Further to protect and support the foot, I provide sock 25 (Figure 2) which is preferably formed of some elastic water-proof material such as lastex. Preferably sock 25 has an open heel, as indicated at 19, and terminates adjacent the

ankle 20. A loop or bight 21 is formed at the lower end of the sock so as to fit between the wearer's first and second toes, thereby to properly position the sock and prevent it from riding up over the arch of the foot. To provide maximum freeness to the toes, the sock is cut away as at 22 and 23 so that the toes freely protrude therefrom. As is better shown in Figure 3, a pad 24 of soft sponge rubber or the like is secured in any suitable manner to sock 25 in such a position as to cushion the ball of the foot, and accordingly protect this portion of the foot against sharp stones, pebbles, or the like. Thus it may be seen that when both shoe 10 and sock 25 are on the foot, the foot is given substantially that measure of support and protection afforded by a conventional high heeled shoe. By reason of the nature of the materials used in the shoe and sock, both are well able to withstand the normal conditions of use of the shoe, the foot has ample freedom and is freely flexible so as to facilitate swimming, and the shoe and sock are so light as not to act as a drag on the foot.

Accordingly I have provided a shoe which attains the several objects of my invention in a 25 thoroughly practical and efficient manner.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. A shoe comprising, in combination, a heel of substantial height and formed from light-weight, water-proof material, a pair of sides connected to said heel and extending upwardly therefrom, a rigid sole secured to said heel and adapted to extend therefrom beneath the wearer's instep and terminating at a point short of the ball of the wearer's foot, a water resistant inner sole secured to said rigid sole and extending over the forward edge thereof, and means connected to said sides for holding the shoe on the foot.
- 5 2. A shoe comprising, in combination, a heel of substantial height, a rigid sole secured to said heel and extending forwardly therefrom and terminating at a point short of the ball of the wearer's foot, cushioning means secured to the upper part of said sole, and means connected to the sides of said shoe for holding the shoe on the wearer's foot.
- 10 3. A heel-counter unit comprising, in combination, a heel of substantial height formed of water resistant material and extending from the back of the wearer's foot beneath the wearer's instep to a point adjacent the ball of the wearer's foot, means secured to the rear portion of said heel for holding said heel from sliding forwardly on the wearer's foot, means extending upwardly from each forward side portion of said heel and over the wearer's arch for detachably securing said heel-counter unit on the wearer's foot, and an inner sole on that portion of said heel about which the wearer's foot is supported.
